CLAIM

I claim the ornamental design for a walker foot skirt, as shown and described.

DESCRIPTION

FIG. 1 is a front perspective view of a walker foot skirt showing the design;

FIG. 2 is a front perspective view from the bottom thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a bottom plan view thereof;

FIG. 8 is a top plan view thereof;

FIG. 9 is a front perspective view of a walker foot skirt in use;

FIG. 10 is a front elevational view of a walker foot skirt showing the design in use;

FIG. 11 is a front perspective view from the top of a walker foot skirt showing the design in use; and,

FIG. 12 is a front elevational view from the bottom of a walker foot skirt showing the design in use.

The broken line showing of the walker and attached tennis balls is included for the purpose of illustrating use and environment and forms no part of the claimed design. The broken lines on the surface of the walker foot skirt represent stitching and form part of the claimed design.
